UNITED STATES PATENT OFFICE

DANIEL H. CHASON, OF ELIZABETH, NEW JERSEY, ASSIGNOR TO THE SINGER MANUFACTURING COMPANY, OF ELIZABETH, NEW JERSEY, A CORPORATION OF NEW JERSEY

DESIGN FOR A HAND LIFT FOR A PORTABLE SEWING MACHINE CABINET

Application filed May 14, 1929. Serial No. 31,210. Term of patent 14 years.

To all whom it may concern:

Be it known that I, DANIEL H. CHASON, a citizen of the United States, residing at Elizabeth, in the county of Union and State of New Jersey, have invented a new, original, and ornamental Design for Hand Lifts for Portable Sewing Machine Cabinets, of which the following is a specification, reference being had therein to the accompanying drawings.

Figs. 1, 2, 3 and 4 are, respectively, side elevation, top plan, end elevation and perspective views of a hand lift for a portable sewing machine cabinet, showing my new design.

I claim:

The ornamental design for a hand lift for a portable sewing machine cabinet, as shown.

In testimony whereof I have signed my name to this specification.

DANIEL H. CHASON.
